UNITED STATES PATENT OFFICE.

CHARLES H. CROWELL, OF SWAMPSOFT, MASSACHUSETTS.

STAY-STRIP.

1,149,344.

Specification of Letters Patent. Patented Aug. 10, 1915.

Application filed August 25, 1911. Serial No. 646,059.

To all whom it may concern:

Be it known that I, CHARLES H. CROWELL, citizen of the United States, residing at Swampscott, county of Essex, State of Massachusetts, have invented a certain new and useful Improvement in Stay-Strips, of which the following is a specification, reference being had therein to the accompanying drawings.

10 My invention relates to a gummed stay strip and process of making the same, said strip being adapted to be folded along a straight line lengthwise of the strip. Such stay strips are generally used to stay the 15 corners of boxes and their construction is such in a manner as to adapt them to be readily folded longitudinally at the corner of the box and attached to the two adjoining sides of the box in the manner well 20 known to those skilled in the art.

Various kinds of gummed strips have been hitherto made but so far as known to me they have been found in practice to be more or less objectionable for various reasons.

25 The object of my invention is to provide a gummed stay strip which will fold readily, neatly and accurately along a line lengthwise of the strip, which will not be 30 weakened at the folding line, and which will adhere smoothly and evenly throughout its entire surface to the adjoining sides of the box or other object to which it may be applied.

35 The nature of the invention is fully set forth in the following description taken in connection with the accompanying drawings, and the novel features thereof are particularly pointed out and clearly defined in 40 the claim at the close of this specification.

In the drawings, Figure 1 is a perspective on an enlarged scale of a piece of gummed stay strip embodying my invention. Fig. 2 is an end view of the strip shown in Fig. 1, 45 also enlarged to more clearly show the construction.

Referring to the drawings A represents a piece of gummed stay strip embodying my invention. In practice these gummed strips 50 are made of various widths and lengths and are usually for convenience in shipment and use coiled into rolls or coils containing a given number of yards. This strip A comprises a body 2 which may be of cloth, paper

or other suitable material. I form in this 55 strip along the line lengthwise thereof at which the strip is intended to be folded a depression 3 which in cross section is rounded as shown. The depth of this depression is preferably about one-half of the 60 thickness of the material of the strip. The depression 3 is not formed by cutting or otherwise impairing the material of the strip 2 but is formed by calendering process, that is by passing the strip between a 65 roll having a flat periphery and a narrow or thin roll with a rounded edge corresponding in shape with the shape of the depression 3. The effect is to calender and densify the paper at this point and form a depression. 70 This depression may obviously vary considerably in width. After being thus treated the strip has a depression lengthwise on one surface and is smooth on the other surface. After this calendering operation the 75 strip is coated with a layer of adhesive 4 in the well known manner. The adhesive fills the depression 3 and presents when dry a smooth surface so that the finished strip is smooth on both surfaces, that is has no depression or projection on either face thereof. 80 If a more or less transparent adhesive be used, as is generally the case, the greater depth or thickness of adhesive in the depression 3 will serve to slightly darken the 85 surface of the material over the depression 3 and will thus make it possible to detect visually the position of the depression. A strip of this kind having in the body or backing thereof a depression formed as 90 above set forth by calendering and having the depression entirely filled by adhesive will fold neatly and accurately along the line of the depression, will be very strong, at the folding line, in fact stronger than at 95 other points due to the increased quantity of adhesive which fills the depression, while the strength of the strip at and beneath the depression is fully preserved, and will adhere very easily and uniformly to the 100 surfaces to which it may be applied.

What I claim is;

As an article of manufacture, a gummed stay strip comprising a body of sheet material having in one face a longitudinal 105 groove, the opposite face being level throughout, the portion of said body between the base of the groove and the oppo-

site face being of greater density than the thicker portions of the body outside of the groove, in combination with a coating of dry adhesive over that face of the body which contains the groove, said adhesive filling the groove up to a level with the face of the coating outside of the groove whereby the strip formed of the combined body and

coating is of uniform thickness and has a level surface on both front and back faces. 10

In testimony whereof I affix my signature, in presence of two witnesses.

CHARLES H. CROWELL.
